UNITED STATES PATENT OFFICE.

GEORG NOBST AND ERNST ULRICH, OF MITTWEIDA, GERMANY, ASSIGNEES TO WILHELM LEILICH, OF CHEMNITZ, GERMANY.

KNITTING MACHINE.

Application filed September 30, 1927, Serial No. 223,135, and in Germany July 15, 1926.

This invention pertains to knitting machines of the type in which independent needles are moved through a stitch forming cycle by appropriate cam devices and relates more particularly to knitting machines wherein needle-operating jacks are interposed between some or all of the needles and the needle actuating cams, and comprising means positively controlling the jacks and operative at predetermined times to disengage certain or all of the jacks from their respective needles in order to produce patterns or other effects in the knitted fabric.

Various devices have heretofore been employed for disengaging the jacks from the needles at the proper time, usually by cam surfaces on the needle bed, which arrangements known to us have been open to serious objection, including the annoyance caused from the accumulation of dust and dirt in the wide needle slot necessary for accommodating the jacks; the inability of the machine to operate at a speed approximately that of ordinary circular machines or to produce more than a very limited number of designs and particularly the impossibility of varying the design from course to course or in the same course; the inadaptability of the mechanism to jacquard control of the jacks; and especially the lack of accuracy, frequent breakage, and need of constant attention due to the rapid wear of the jacks and cooperating parts by reason of the harsh motions and the very small and inadequate bearing surfaces commonly provided.

In accordance with the present invention we provide positive means for engaging and disengaging the jacks from the needles which is applicable to a machine (whether flat or circular and whether the needle bed or the cam carrier be the moving part) having a needle bed of ordinary type except that the slots or needle grooves are cut somewhat deeper than normal; which may be applied to machines of fine, as well as coarse gage; which permits variations in the pattern from course to course and even in the same course, if desired; which is readily adaptable to jacquard control; and wherein, by the provision of adequate bearing surfaces, rapid wear and cutting of the cylinder or needle bed and breakage of the jacks and associated elements is reduced to a minimum. In arriving at the above result we provide means, to wit cams on the cam carrier of the machine for rocking the jacks

independently of their longitudinal movement, whereby to engage and disengage them from the needles, preferably employing cam elements which keep the jacks under substantially positive control to avoid accidental engagement or release of the needles. In order to insure both positive retraction and advance of the needles, and to prevent over-retraction of the needles, particularly when the needle beds are vertical, we prefer to make the jacks in two parts, preferably articulated to permit outward swing of one part relative to the other, and provide one element of the jack with a needle retracting hook and the other with a pusher surface of adequate area to insure reliable engagement with the end of the needle.

Although in its broader aspects the invention is applicable to machines having a single needle bed (flat or cylindrical) we find it particularly advantageous in its application to a machine having a plurality of needle beds and adapted to produce fabrics exhibiting a ribbed effect, a purled effect or both such effects. In the accompanying drawings we have illustrated the invention as embodied in a circular knitting machine having an upper and a lower needle cylinder of the same diameter and arranged in axial alignment and employing double-ended needles which may slide from the groove of one cylinder into an aligned groove of the other cylinder and which are adapted to draw stitches when in either cylinder. Such machines are in general well known, together with their capability to knit either plain ribbed or purled work, or combinations thereof, and in the drawings and descriptions we shall confine ourselves quite closely to a disclosure of our improved needle actuating jacks and the cams for operating the same, it being understood that usual adjunctive features, such, for example, as the means for rotating (or reciprocating) the needle cylinder (or the cam cylinder, if that be the moving part), the yarn feeding means, narrowing and widening devices, if such be employed, take-up and tension means, etc., may be of any known and appropriate type familiar to those skilled in the art.

In the drawings

Fig. 1 is a side elevation of a needle jack embodying certain features of our present invention;

Fig. 2 is a similar elevation, illustrating a

preferred form of needle-actuating jack consisting of two relatively movable members, one of which performs the needle retracting function and the other the needle advancing function;

5 Fig. 3 is a vertical diametrical section through a knitting machine of the type referred to, equipped with our improved needle-actuating jacks;

10 Fig. 4 is a development of the cam cylinder of a knitting machine adapted for use with our improved jacks;

15 Fig. 4^a is a composite diagrammatic section through the cam cylinder substantially on the lines A—A, B—B and D—D, respectively; and

20 Figs. 5 and 6 are elevations illustrating various types of fabrics which may be knitted upon the machine herein disclosed.

25 Referring to the drawings, and particularly to Fig. 1, we have illustrated a one-piece needle jack which may be made of a thickness substantially to fill the needle groove and which comprises the head portion *a* and a tail portion *f* disposed at an oblique angle to each other and having substantially straight inner edges *a''* and *f''* meeting at the point *g*, all of said parts being in the same plane. The part *a* is provided with the needle retracting hook 30 *b*, below which is a recess for the reception of the needle hook, the lower wall of the recess constituting a pusher element *c* for engagement with the outer end surface of the needle hook. The outer edge of this jack is furnished with an actuating butt *h*, preferably disposed at a point opposite the point *g*. When a jack of this type is employed it may be caused to rock about the point *g* to move its hook *b* into and out of engagement with 35 the needle, and whether engaging the needle or disengaged therefrom, this jack presents an elongate bearing surface *a'* or *f'*, respectively, for engagement with the bottom of the cylinder groove and does not tend to cut into the cylinder or itself to wear rapidly.

40 While we may, under some circumstances, particularly in coarse gage machines, employ a jack such as shown in Fig. 1, we prefer to employ the composite jack illustrated in Fig. 45 2. The jack shown in Fig. 2 has a retracting element substantially similar to the jack shown in Fig. 1, comprising the parts *a* and *f*, the hook *b*, and the butt *h*, the parts *a* and *f* making an obtuse angle with each other and 50 having their inner straight edges lying in a direction to meet substantially at the point *g*. In this instance we provide a recess or socket at the point *i* closely adjacent to the point *g*. With this retracting jack element 55 we combine a separate needle advancing or pusher element *s*. This advancing element is a substantially straight bar having a butt *p* which loosely engages the socket *i* in the retracting element of the jack, thus articulating 60 the retracting and advancing members of

the jack. The advancing element *s* has a pusher surface *s'* at its end of adequate width to insure proper engagement with the end of the needle, and which is normally spaced from the hooks *b* of the retractor element so as to furnish the recess *c* of sufficient size to receive the needle hook. The advancer or pusher element *s* is provided with a substantially straight inner surface or edge *s''* which engages the bottom of the needle groove. 70 The needle groove may be of usual type having its inner wall substantially straight, but should be of sufficient depth to accommodate the composite jacks comprising the retracting and advancing elements above described. 75

80 In Fig. 3 we have illustrated our improved needle actuating jack as applied to a knitting machine of circular type having the lower cylinder *C* and the upper cylinder *C'* which are of substantially the same diameter 85 and arranged in axial alignment and suitably spaced at their adjacent ends to provide for the passage of the knitted web. A cam cylinder *C''* cooperates with the needles and needle jacks carried by the needle cylinders. 90 As the machine here illustrated is of that type in which the cam cylinders rotate, while the needle cylinders remain relatively stationary, it is possible to employ a single cam cylinder furnished with one or more openings at the 95 desired point or points for admission of any usual yarn feed elements, etc., but, if desired, independent cam cylinders may be provided for cooperation with the upper and lower 100 needle cylinders, respectively.

105 The needle grooves in the cylinders *C* and *C'* are in alignment and each pair of aligned grooves in the two cylinders may be considered as constituting upper and lower portions of a single groove. A needle *e* is arranged to slide in each needle groove and to be transferred from the lower portion of the groove (in the cylinder *C*) to the upper portion of the groove (in the cylinder *C'*) and vice versa. The needles here shown are latch needles and 110 each needle is furnished with a head or hook at each end. Each groove of the lower cylinder *C* and each groove of the upper cylinder *C'* is preferably provided with a jack *a* *f* of the type shown in Fig. 2. While, under ordinary circumstances, a double-ended needle is provided for each composite needle groove and a jack is disposed in each groove of each needle cylinder, it is obviously within the 115 scope of the invention to omit needles or jacks from or change to other well-known forms of needles or jacks for certain of the grooves.

120 The cam cylinder *C''* is furnished with jack-actuating cams providing a groove *h* for the reception of the butts *h* of the lower series of jacks and with a groove *h'* for the reception of the butts *h* of the upper series of needle jacks. The cam cylinder also has jack-actuating needle-retracting cams *T* and *T'* and corresponding advancing cams of any usual type. 125

The upper cam groove k' is wider than the lower groove k , at least at that portion in advance of the knitting cams, so as to permit the butts of the jacks to be raised out of their usual path to an inoperative position, and for selectively raising the jacks to this upper or idle position we provide the adjustable switch cam v which, under normal circumstances, is aligned with the bottom of the cam groove k' as shown in full lines in Fig. 4, but which may be raised to the inclined position indicated in dotted lines in the same figure. When the cam v is in its normal position, the butts h of the upper series of jacks move along over the top of this cam v without actuation thereby and are not retracted until they engage the advancing slope of cam 3^a forming the lower edge of the wider part of groove k' ahead of cam T' , Fig. 4.

The inner faces of the cam rings 1 and 2 which define the grooves k and 3 and 4 , which define groove k' are so shaped as to rock the jacks, or at least the retracting portions of the jacks, in and out, toward and from the needle cylinders. Thus, throughout the main portion of the circumference of the cam cylinder, (Fig. 4^a, section D) the cam element 1 above the groove k and the cam element 3 below the groove k' have inclined or beveled faces as also indicated at the left side of Fig. 3, which permit the hook ends of the jacks to swing outwardly away from the needle cylinders. At the same portions of the cam cylinder, the cam elements 2 and 4, which engage the tails of the jacks, are of substantially rectangular cross section in any radial plane, as shown at the left-hand side of Fig. 3, so as positively to maintain the jacks rocked on their points g into inoperative position, that is to say, with their hook ends outwardly away from the needles. However, at about the radial plane indicated by the line A (Fig. 4) the element 1 in the lower part of the cam cylinder merges into a portion 1^a which is substantially rectangular, (Fig. 4^a, section A) while the element 2 merges into a portion 2^a which is beveled or inclined. As a jack of the lower series passes the point A the cam elements 1^a and 2^a swing the jack so that its head moves radially inward into position to engage the hooks of a needle properly positioned to receive it.

On the other hand the cam element 3 of the upper portion of the cam cylinder at substantially the plane B ahead of plane A merges into a part 3^a of rectangular section, (Fig. 4^a, section B) while the cam element 4 at the same plane B merges into a part 4^a of beveled or inclined section. Thus, as the jacks of the upper series pass the plane B, their heads or hook portions begin to swing inwardly into position to engage the hook of a needle.

Since the plane B is in advance of the point A in the direction of rotation of the cam cylinder so that under ordinary circum-

stances the jacks of the upper series are swung into operative position before those of the lower series and needles engaged by them are moved by the upper jack cams T' . It may also be noted that the cam groove k is furnished with a retracting portion k^2 just to the left, as shown in Fig. 4, of the plane A, and that the riser cam slope of cam 3^a is disposed immediately to the left of the point at which the jacks of the upper series have been swung into full engagement with the needle hooks.

For the production of the class of work now to be described, suitable pattern mechanism of usual and well-known type is provided which moves the cam v upwardly into the dotted line position during one rotation of the cam cylinder and then down into the full line position during the subsequent rotation but it is to be understood that this cam may be moved by hand if desired, and that it may be moved in accordance with any other desired pattern sequence by the use of appropriate mechanism familiar to those skilled in the art.

The fabric now to be described is that sometimes called "purl" knitting in which alternate rows (courses) of stitches are drawn to opposite sides of the fabric, producing a transverse ribbed effect. Assuming that, during the first course the cam v is in its full line position and that all of the needles are in a central or neutral position in which they extend across the gap between the cylinders C and C' with their previously formed loops hanging upon their shanks, and that all of the needle actuating jacks are out of engagement with the needles, (see left side of Fig. 3), rotation of the cam cylinder causes the cam elements 3^a and 4^a to swing the jacks of the upper series into position to engage the upper needle hooks before the lower series of jacks are thus moved. The butts of the upper jacks immediately thereafter engage the slope of cam 3^a , thus moving the needles up and out of the grasp of the lower jacks as the latter are subsequently swung inward by the action of the elements 1^a and 2^a at and beyond plane A. Therefore, the lower series of jacks move downwardly free of the needles, and at the same time the upper series of jacks, engaging the needles, are actuated by the knitting cam T' to draw a new series of loops. After passing the knitting cam T' the pusher elements of the upper jacks move the needles back to the central or neutral position and all of the jacks, in both the upper and lower series, are immediately swung outwardly by engagement with the cam elements $3, 4, 1$ and 2 , respectively. Upon the next rotation of the cam cylinder the cam v is raised to the dotted line position, and as the butts of the upper series of jacks engage this cam, they are lifted to an idle position before they are swung

inwardly by the elements 3^a and 4^a. As the jacks of the lower series are swung inwardly by the cam elements 1^a and 2^a, they find the needles in position to be engaged by their 5 hooks and these latter jacks immediately engage the slope k² and are drawn safely down and into position to engage knitting cams T and thereby to form a series of loops over the verge of the lower cylinder.

10 By a continuation of the above double cycle, purl fabrics of any desired extent may be knitted while it is obvious that by allowing the cam v to remain continuously either in its up or down position, plain fabric of any 15 desired number of courses may be knitted having its loops all drawn to one face or to the other, depending upon the cylinder which, for the time being, is active.

It is obvious that by raising and lowering 20 the cam v or otherwise determining the vertical position of jacks a f ahead of plane B at regular intervals during the formation of a single course, a certain definite number of needles will knit in one cylinder and another group will knit in the other cylinder, thus producing fabrics having ribbed stripes of any desired width, as shown in Fig. 5. Moreover, by a combination of the above operations, fabric having both horizontal and 25 vertical stripes may be produced, thus giving a checked effect as indicated, for example, in Fig. 6, where courses of plain knitting are indicated at 1 and at 11 and 12, alternating with courses (2 to 10, inclusive) of fabric 30 containing vertical rib stripes.

35 Preferably, in order to prevent over-retraction of the needles of the lower series, we provide any usual guard z for pusher jacks s below the knitting cam T, Figs. 3 and 4.

The provision of the wide groove k' in the upper part of the cam cylinder permits the jacks to be moved upwardly to idle position by the cam v, as above described, and it further permits lifting of any of these jacks by jacquard mechanism of any desired type, adapted, for example, to move individual jacks to idle upper position while leaving other jacks in active lower position. For 45 this purpose some or all of the jacks may be provided with openings w for the reception of the jacquard cords. It is thus possible to produce varied ornamental effects through the employment of these jacks without adding greatly to the complexity of the mechanism and without undue cost of production or decrease in speed, it being noted that the mechanism here disclosed is capable of operation at substantially the same speed as a 50 plain knitting machine.

55 During all of the movements of the jacks above described, the jacks bear over a long and substantially straight surface against the inner wall of the needle groove; the rocking of the jack is occasioned by the engage-

ment of broad cam faces with extended surfaces of the jack so that there is little tendency to wear and cut either the jack or the cam element; the needle grooves are of normal width so that there is no abnormal tendency for dirt and dust to accumulate therein; the machine may be made of fine gage since the jacks occupy no more circumferential width than the needles, and the needle-actuating jacks are applicable to machines primarily intended for producing work of almost any type. In our copending applications Serial Nos. 249,631 and 249,628, we have explained how a knitting machine of these capabilities may be utilized for heel and toe 80 fashioning with the aid of jacquard control.

85 As above described, the improved jacks are particularly well suited for use in a multiple-cylinder machine as hereinabove disclosed, but they are also useful in connection with any other form of needle or element capable of being engaged and worked by them. While particular reference in the above description has been made to the two-part jacks shown in Fig. 2, we contemplate that a jack 90 such as shown in Fig. 1 may, under some circumstances, be employed, such jack being somewhat simpler and cheaper to make, and functioning in a very acceptable manner under most conditions of use.

95 We claim:

1. In a knitting machine having a grooved needle bed and a cam carrier, a needle actuating jack arranged to slide longitudinally in a groove of the needle bed, said jack comprising a head portion and a tail portion disposed at an angle to one another, the jack being adapted to rock about the point of union of its head and tail portions, cam means on the cam carrier for moving the head of the jack toward and from needle engaging position, said cam means having parts acting on the same face of the jack cooperating positively with said head and tail portions to control the position of the jack in 110 the intervals between such movements.

2. In a knitting machine having a grooved needle bed and a cam carrier, a needle actuating jack arranged to slide longitudinally in a groove of the needle bed, said jack comprising a member having angularly disposed elements with straight edges lying in a direction to converge at a point about which said member may rock as an axis, and positioning means constantly engaging the exterior face of said jack at opposite sides of said point, said positioning means including cams for rocking the jack whereby to engage it with and to disengage it from its needle.

3. In a knitting machine having a grooved needle bed and a relatively movable cam carrier, a needle actuating jack sliding in a groove of the needle bed, said jack comprising a needle advancing member, a needle retracting member fulcrumed to rock relatively 125

- to the advancing member, one of said members having an actuating butt, a cam on the cam carrier engageable with said butt, and spaced positioning elements constantly engaging the needle retracting member on one of its faces at opposite sides of its fulcrum, respectively, said elements comprising cams for rocking the needle retracting member toward and from needle engaging position.
- 10 4. In a knitting machine having a grooved needle bed and a relatively movable cam carrier, a needle actuating jack sliding in a groove of the needle bed, said jack comprising a needle advancing member, a needle re-
tracting member having a recess in its inner edge, a butt on the advancing member engag-
ing said recess, a butt on the outer edge of the re-
tracting member, cam means on the cam car-
rier engaging the butt on the retracting mem-
ber for moving said member longitudinally in
the needle groove, and means on the cam car-
rier engageable with the outer edge of the re-
tracting member at opposite sides of said butt
for positioning said retracting member at all
25 times, said means comprising cams for mov-
ing the retracting member relatively to the
advancing member.
5. In a circular knitting machine having a
grooved needle bed and a relatively movable
30 cam carrier, a needle actuating jack sliding
in a groove of the needle bed, said jack com-
prising a needle advancing member, a needle
retracting member articulated to the outer
edge of the advancing member to rock toward
35 and from the latter, a cam on the cam carrier
for moving the entire jack longitudinally of
the needle groove, and means constantly en-
gaging said retracting member including
cams spaced longitudinally of the needle
40 grooves and engageable with said retracting
member at opposite sides respectively of its
point of articulation for rocking the retract-
ing member toward and from needle engag-
ing position.
- 45 6. In a circular knitting machine having a
grooved needle bed and a relatively movable
cam carrier, a needle driving jack sliding
longitudinally in a groove of the needle bed,
said jack having an element engageable with
50 a needle for retracting the needle in its groove,
means for advancing and retracting the jack
longitudinally of the groove, and cam means
operative in a fixed circumferential position
55 in relation to said advancing and retracting
cams independently of the longitudinal pos-
ition of the jack and while the latter is fully
advanced to act in the direction of a radius
of the machine for moving the jack into needle
engaging position.
- 60 7. In a circular knitting machine of the
class described having a grooved needle bed
and a relatively movable cam carrier, a needle
actuating jack sliding longitudinally in a
groove of the needle bed, said jack having a
substantially straight inner edge engaging
the bottom of the needle groove and comprising
an element engageable with a needle for
retracting the needle in its groove and an ele-
ment for advancing the needle in its groove,
a knitting cam for moving the jack longitudi-
nally of its groove, and cam means on the cam
carrier for moving the retracting element of
the jack into needle engaging position as it ap-
proaches the knitting cam and out of needle
engaging position after it leaves the knitting
cam, and for positively positioning it in the
intervals between successive engagements by
the knitting cam.
8. In a knitting machine comprising two
grooved needle beds having their respective
grooves in alignment, double ended needles
adapted to slide from one bed into the other,
a cam carrier, a needle driving jack in each
groove of each bed, each jack having a part
engageable with a needle for imparting move-
ment thereto, knitting cams on the cam car-
rier for advancing and retracting the jacks
longitudinally in the needle grooves, and cam
means on the cam carrier engaging with the
outer edges of the jacks at all times whereby
positively to position the jacks and adapted
to hold the jacks out of engagement with their
needles in the intervals between successive
operations of the jacks by the knitting cams.
9. In a circular knitting machine of the
class described having a grooved needle bed
and a relatively movable cam carrier, a needle
actuating jack sliding in a groove of the
needle bed, said jack comprising a needle ad-
vancing member having a substantially
10 straight surface engaging the bottom of the
needle groove and a needle retracting member
articulated to the advancing member and
adapted to swing toward and from the bot-
tom wall of the needle groove, and a pair of
105 rings on the cam carrier, said rings having
inner circumferential surfaces engageable
with the edge of the needle retracting member
at opposite sides respectively of its point of
articulation, the inner surfaces of said rings
110 having cylindrical and conical portions, a
conical portion of one ring cooperating with a
cylindrical portion of the other to determine
the position of the jack.
10. In a circular knitting machine of the
class described having a grooved needle bed
and a cam carrier, a needle actuating jack ar-
ranged to slide longitudinally in a groove of
the needle bed, said jack comprising a part en-
gageable with a needle for imparting move-
ment of the jack thereto, a knitting cam for
moving the jack longitudinally of the groove
to actuate its needle for knitting, controlling
cam means acting independently of the longi-
tudinal movement of the jack in its groove to
bring said part of the jack into engagement
120 with the needle, and movable means adapted
to be moved from time to time to move the

jack out of range of effective operation of said controlling cam means before the jack engages the knitting cam.

11. In a circular knitting machine of the class described comprising two needle beds having their respective grooves disposed in alignment, double ended needles adapted to slide from grooves of one bed into the corresponding grooves of the other, a cam carrier, a needle actuating jack disposed in each groove of each needle bed in alignment with the needles therein, knitting cams on the cam carrier adapted to engage the jacks and thereby to advance and retract all of the jacks during each cycle of operation of the machine, and controlling cams on the cam carrier for moving all of the jacks into needle engaging position as the jacks approach the knitting cams, the controlling cams being arranged to 20 actuate the jacks in one needle bed prior to those in the other.

12. In a knitting machine comprising two grooved needle beds having their respective grooves disposed in alignment, double ended needles adapted to slide from grooves of one bed into the corresponding grooves of the other, a cam carrier, a series of needle actuating jacks disposed in the grooves of each needle bed in alignment with the needles therein, knitting cams on the cam carrier engageable with the jacks thereby to advance and retract the jacks during each cycle of operation of the machine, means normally holding all of the jacks except those in the vicinity 35 of the knitting cams out of engagement with the needles, means on the cam carrier for moving the jacks into engagement with the needles as the knitting cams and jacks approach each other, and movable means adjustable to a position such as to retract jacks in one needle bed before they engage their needles.

13. In a knitting machine comprising two grooved needle beds having their respective grooves disposed in alignment, double ended needles adapted to slide from grooves of one bed into the corresponding grooves of the other, a cam carrier, a series of needle actuating jacks disposed in the grooves of each needle bed and in alignment with the needles therein, knitting and other cams on the carrier for advancing and retracting the jacks during each cycle of operation of the machine, said cams being arranged to retract the jacks in one bed prior to those in the other, means on the cam carrier adapted to cause the jacks in the said bed to move to needle engaging position before the jacks in the other bed are moved to such position, and means for re-60 tracting jacks of said bed before they have engaged any needle.

14. In a circular independent needle knitting machine of the class described having upper and lower axially aligned rotary needle cylinders and relatively stationary knitting

cams, double ended needles adapted to slide from a groove of one cylinder into the corresponding groove of the other cylinder, a series of needle actuating jacks in the grooves of the upper and lower cylinders, said jacks having needle engaging parts and butts for cooperation with the knitting cams, means holding both series of jacks out of engagement with the needles except adjacent to the stitch forming point, cam elements, fixed relatively to the knitting cams, for moving the jacks into engagement with the needles as the jacks approach the knitting cams, and a cam adjustable to a position such as to retract the jacks of one series before they are moved to needle engaging position.

15. In a circular knitting machine comprising upper and lower grooved needle beds having their respective grooves disposed in alignment, double ended needles adapted to slide from grooves of one bed into the corresponding grooves of the other, a cam carrier, a series of needle actuating jacks disposed in the grooves of each needle bed in alignment with the needles therein, knitting cams on the cam carrier for advancing and retracting all of the jacks during each cycle of the machine, said knitting cams normally retracting the jacks in the upper bed prior to those in the lower bed, means for moving the jacks into and out of engagement with the needles, said latter means moving the jacks in the upper bed into needle engaging position prior to their retraction by the knitting cams, and means including an adjustable cam on the cam carrier adapted to retract the jacks in the upper bed before they have moved to needle engaging position.

16. In a circular independent needle knitting machine having upper and lower axially aligned rotary needle cylinders and relatively stationary knitting cams, double ended needles adapted to slide from the grooves of one cylinder into the corresponding grooves of the other cylinder, a series of needle actuating jacks in the grooves of the upper and lower cylinders, said jacks having needle engaging parts and butts for cooperation with the knitting cams, and means including two pairs of spaced circumferentially extending cam rings respectively for said upper and lower cylinders in circumferential positions fixed in relation to the knitting cams and having circular and eccentric portions adapted normally to act in the direction of a radius of the machine to hold the jacks out of engagement with the needles and to move the jacks into needle engaging position as they approach the knitting cams.

In testimony whereof, we have signed our names to this specification this 25th day of August, 1927.

GEORG NOBST.
ERNST ULRICH.
